UNITED STATES PATENT OFFICE.

WILLIAM W. BLAISDELL, OF NEW YORK, N. Y.

METHOD OF TREATING OIL SHALES AND OTHER BITUMINOUS MATERIALS.

Application filed May 3, 1923. Serial No. 636,410.

This invention relates to the treatment of oil bearing shales and other bituminous materials, and particularly to the method for extracting the hydrocarbon content in an efficient and economical manner.

The treatment of various shales by various methods and with various apparatus has been heretofore practiced with some success, but on account of the character of most shales 10 actual commercial production has not generally been profitable.

One of the difficulties in the treatment of these shales in quantity has been that of applying suitable temperatures to the shale 15 without having local condensations, coking and the like, due to its slow absorption of heat. All such effects are restrictive of the output and add to the difficulty of handling the shale in quantities sufficient to make commercial production profitable.

Under my method and particularly with apparatus such as I shall herein discuss and show as illustrative of the principles involved, shales of ordinary grade may be 25 handled in quantity economically and efficiently. My invention may best be understood by reference to operations and constructions illustrative of practical conditions, and for this purpose I have shown in the 30 accompanying drawings an illustrative plant operating in accordance with my invention. In these drawings:

Fig. 1 illustrates, partly in section apparatus for carrying out my method for the 35 treatment of such shale.

Fig. 2 is a detail in section of the super-heater of the same, and

Fig. 3 is a partial view in perspective of such equipment.

Before discussing the actual apparatus as shown, it is desirable to consider first my general method and the reasons therefor and the results obtained thereby. In the first place, my invention contemplates a 40 methodical and uniform pre-heating of the shale for the purpose of bringing it uniformly to a temperature just below the volatilizing point of its hydrocarbon content. I use this term merely to differentiate between the oil production sought and the aqueous elements and gases which pass off at comparatively low temperatures. Roughly speaking, I effect a preliminary uniform heating at a temperature of approximately 50 500° F., that is to say some 100° F., below

the required heat to produce the final volatilization.

This pre-heating in accordance with my invention is very efficiently and satisfactorily accomplished by introducing the heat of the 60 exhaust gases directly into the pre-heater onto the shale itself, which is kept in suspension as far as practicable in the pre-heater, as distinguished from heating the walls of the pre-heater and radiating the heat 65 of the exhaust gases onto the shale, as has heretofore been the practice. This method results in the heat uniformly and thoroughly permeating the shale. Preferably I utilize the heat of the exhaust gases from the 70 final heating step of my method and introduce this heat of the exhaust gases in the form of hot air or gases as a counter-current directly into the flow or feed of comminuted shale so that the shale will be progressively 75 and slowly permeated by the heat of the exhaust gases up to a point just below the formation of bituminous vapors, whereby when the shale reaches the ultimate or super-heater it will be uniformly and thoroughly 80 permeated by the heat of the exhaust gases but without having developed any volatilization. The final heating in the super-heater is a mere rapid raising of the uniformly and thoroughly permeated preheated shale to a 85 temperature sufficient to drive off the more resistant hydrocarbon elements which are led away for condensation into a product 90 which represents practically the total combined hydrocarbon content of the shale.

Coming now to the specific installation illustrated herein it will be seen that I have provided an apparatus consisting of a pre-heater, a super-heater and a condenser.

Pre-heater.

The shale or other bituminous material is discharged from a hopper A through a revolving trap B onto the header of a revolving pipe C, which is mounted in a rotary 100 shell D to revolve therewith. The shale is gradually carried through the pipe C until it drops into shell D where its passage is reversed and the shale is carried back onto the header of shell D. Both the pipe C and shell D are provided with blades E to pick up the material and keep it in suspension during its passage through the pipe and shell. The shell D is revolved from a 105 motor X by means of drive gears W and W¹, 110

idle^s V and V¹ being provided to support the shell while revolving.

The heat of the exhaust gases from the super-heater is passed through a pipe N beneath the header of the pre-heater, the heated gases coming from the superheater being cooled by atmospheric air drawn in by the fan U. This fan also acts to circulate the heat of the exhaust gases through the pipe C and shell D whereby the shale is slowly and uniformly permeated with heat up to a point just below the formation of the hydrocarbon vapors.

If desired, additional burners may be provided to supplement the heat of the exhaust gases from the super-heater. If such supplemental burners are employed, they will be mounted to deliver the heat directly onto the shale. After the preliminary heat of the exhaust gases is circulated through the pre-heater, it is carried out and away through the stack T.

Super-heater.

The pre-heated shale is now passed by way of header F and revolving sealed trap G onto a revolving plate I which is slowly rotated over the burners P of the super-heater by a shaft Q driven from a drive shaft R. The wall of the super-heater chamber is vented as at O, Fig. 1.

At this point the hydrocarbon vapors are formed and carried off during one complete revolution of plate I. The spent shale is then scraped from plate I by a stationary scraper K and dropped through a revolving sealed trap L which prevents the admission of air into the super-heater. From trap L the spent shale drops onto a screw conveyor M which carries it out and away from the super-heater.

The plate I is provided with a dome H constituting therewith the chamber of the super-heater in which the hydrocarbon vapors are formed and these vapors are passed from said chamber to a condenser Y by way of pipe J leading from the dome H. A fan U¹ may be mounted within the pipe J to create a suction effective to assist the passage of the vapors into the condenser Y. The dome H is provided with a series of pockets H¹ which allow free access of the vapors into the pipe J.

Super-heated steam is introduced into said chamber by a steam pipe S. This pipe is provided with downwardly delivering branch pipes S¹ and an upwardly delivering branch pipe S¹¹ extending into header F and adapted to build up a head of steam just below the revolving sealed trap G so as to prevent the hydrocarbon vapors from the chamber of the super-heater entering said trap. This head of steam also creates a slight back pressure which will assist to remove the hydrocarbon vapors from the super-heater through the pipe J and assists to keep the revolving plate I clean.

Condenser.

The condenser Y is not shown in detail, but is provided with any suitable means for cooling the hot hydrocarbon vapors which may then be drawn off through outlet Z of this condenser.

Various modifications in the method of and apparatus for practicing my invention may obviously be resorted to within the limits of the appended claim.

What I therefore claim and desire to secure by Letters Patent is:—

The method of treating shale or other bituminous material, which consists in initially preheating the material to a point somewhat below the point at which the hydrocarbon vapors are formed and in subsequently superheating the material to the point at which said hydrocarbon vapors are formed, the preheating and superheating steps being carried out in separate chambers, and the heat of the exhaust gases from the superheating chamber being used to heat the material in the preheating chamber, in passing the material from the preheating to the superheating chamber, in preventing the escape of vapor during such passage, in reducing the temperature of the heat of the exhaust gases preliminary to its delivery to the pre-heated chamber by introducing atmospheric air in the gases, in mechanically agitating the material in the preheater chamber during treatment, in removing the spent material from the superheater chamber, and in condensing the hydrocarbon vapors.

In testimony wherof I affix my signature.
WILLIAM W. BLAISDELL.
